UNITED STATES PATENT OFFICE.

ARTHUR H. GIBSON, OF EASTON, PENNSYLVANIA, ASSIGNOR TO
INGERSOLL-RAND COMPANY, OF NEW YORK, N. Y., A CORPO-
RATION OF NEW JERSEY.

ELECTROPNEUMATIC CHANNELER.

No. 819,011.

Specification of Letters Patent.

Patented April 24, 1906.

Application filed December 15, 1905. Serial No. 291,842.

To all whom it may concern:

Be it known that I, ARTHUR H. GIBSON, a subject of the King of Great Britain, and a resident of Easton, in the county of Northampton and State of Pennsylvania, have invented a new and useful Improvement in Electropneumatic Channelers, of which the following is a specification.

The object of this present invention is to provide certain improvements in electro-pneumatic channelers, in which the tool-piston is operated by reciprocating columns of air from a presser.

In the accompanying drawings, Figure 1 represents an electropneumatic channeler in side elevation, a portion of the presser being shown in section, the flexible tubes between the presser and tool-cylinder being shown broken away. Fig. 2 represents the tool-cylinder in top plan. Fig. 3 represents the same in longitudinal central section. Fig. 4 is a detail sectional view showing the manually-operated valve for the space at the back side of the tool-piston turned in position to bring the space into open communication with the atmosphere through a restricted outlet. Fig. 5 is a detail section showing the manually-operated valve for controlling communication from the space at the other side of the tool-piston either to the motive-fluid pipe or the reserve-fluid chamber, the valve being shown in position to bring the said space into open communication with the reserve-fluid chamber; and Fig. 6 is an enlarged section of the said valve.

An electropneumatic presser is shown for driving the tool, the motor of which is denoted by 1, the presser-cylinder by 2, and its trunk-piston by 3. Flexible pipes 4 and 5 lead from the spaces 6 and 7 at the back and front of the piston 3 to the spaces 8 and 9 at the front and back of the tool-piston 10 in the tool-cylinder 11. This piston 10 has the usual front rod 12 and tail-rod 13. A manually-operated valve 14 is mounted in the cylinder 11, and passages 15 and 16 lead from the pipe 5 and the space 9 to the face of the said valve. A restricted outlet 17 also leads from the face of the valve 14 to the external atmosphere, and the valve 14 is provided with a port 18, which is arranged to bring the passage 16 from the space 9 into open communication with the pipe 5 or into open communication with the restricted outlet 17 at pleasure.

A second manually-operated valve 19 is mounted in the cylinder 11, and passages 20 and 21 lead from the pipe 4 and space 8, respectively, to the face of the said valve. A third passage 22 leads from the face of the valve 19 to a reserve-fluid chamber 23, in the present instance through a pipe 24. The manually-operated valve 19 is provided with a port 25, which is arranged to bring the passage 21 into open communication with the passage 20, and thereby the pipe 4 into communication with the passage 22, and thereby the chamber 23, at pleasure. Handles 26 and 27 may be provided for the valves 14 and 19.

In operation when both of the spaces 8 and 9 are in open communication with their pipes 4 and 5 the tool-piston will operate in unison with the presser-piston.

When it is desired to reduce the blow of the tool, the space 8 in front of the tool-piston 10 may be closed to the pipe 4 and opened to the reserve-fluid chamber 23. This condition is desirable where it is desired to ease the tool in tight places by working it up and down or to cut through difficult parts where a hard blow would injure the tool.

In order to keep the pressure in the space 8, reserve-fluid chamber 23, and pipe 24 up to the desired pressure to accomplish the above result, it is desirable that a valved passage be arranged in the manually-operated valve 19, through which air may leak from the pipe 4 into the said space, chamber, and pipe, thus overcoming the reduction of pressure owing to leakage past the front rod 12. The valved passage in the valve 19, referred to, comprises a small aperture 19*, controlled by a spring-actuated valve 19**, arranged to permit pressure to pass by the same from the pipe 4, but to close the aperture against the passage of air to the pipe 4.

It will be seen that when the space 8 is closed to the pipe 4 the presser has to compress all of its lifting air into the pipe 4, thus raising the air to a higher pressure than is usual and imposing a higher torque on the presser crank-shaft than where the tool is working in unison with the presser, but consumes no power, since the crank-shaft receives the energy back again after turning over at center.

When it is desired to dislodge the tool after

it has been become jammed, the valve 14 is turned into position to cut off communication from the space 9 back of the tool-piston to the pipe 5 and at the same time open communication from the space 9 to atmosphere through the restricted outlet 17.

It is to be understood that the valve 19 is in position to open communication from the space 8 in front of the piston to the pipe 4. 10 This arrangement will eliminate the pressure at the back of the tool-piston 10 and permit the utilization of all of the pressure in front of the piston. As the piston rises under this abnormal pressure it will be prevented from 15 striking the back head of the cylinder because of the restricted outlet 17 being sufficiently small to cause the air back of the piston to cushion it to a sufficient extent.

While I have shown the tool-cylinder in 20 the accompanying drawings as disposed horizontally, it is to be understood that it may be used either horizontally or vertically or at any angle desired to suit the work to be done.

What I claim is—

25 1. A tool-piston, its cylinder, pipes for supplying motive fluid alternately to the opposite sides of the piston and means for closing communication between the space at one side of the piston and one of the pipes and opening the said space to atmosphere.

30 2. A tool-piston, its cylinder, pipes for supplying motive fluid alternately to the opposite sides of the piston and means for closing communication between the space at one side of the piston and one of the pipes and opening the said space to atmosphere through a restricted outlet.

35 3. A tool-piston, its cylinder, pipes for supplying motive fluid alternately to the opposite sides of the piston and means for closing communication between the space at the back side of the piston and one of the pipes and opening the said space to atmosphere.

40 4. A tool-piston, its cylinder, pipes for supplying motive fluid alternately to the opposite sides of the piston and means for closing communication between the space at the back side of the piston and one of the pipes and opening the said space to atmosphere

45 through a restricted outlet.

50 5. A tool-piston, its cylinder, pipes for supplying motive fluid alternately to the opposite sides of the piston and a manually-operated valve for closing communication between the space at one side of the piston and one of the pipes and opening the said space to atmosphere.

55 6. A tool-piston, its cylinder, pipes for supplying motive fluid alternately to the opposite sides of the piston and a manually-operated valve for closing communication between the space at one side of the piston and one of the pipes and opening the said space to atmosphere through a restricted outlet.

60 65 7. A tool-piston, its cylinder, pipes for sup-

plying motive fluid alternately to the opposite sides of the piston and a manually-operated valve for closing communication between the space at the back side of the piston, and one of the pipes, and opening the said space to atmosphere.

70 8. A tool-piston, its cylinder, pipes for supplying motive fluid alternately to the opposite sides of the piston and a manually-operated valve for closing communication between the space at the back side of the piston and one of the pipes and opening the said space to atmosphere through a restricted outlet.

75 80 9. A tool-piston, its cylinder, pipes for supplying motive fluid alternately to the opposite sides of the piston, a reserve-fluid chamber, a valve and passages leading respectively from one of the pipes, from the space at one side of the piston and from the reserve-fluid chamber to the face of the valve, the said valve being arranged to close communication between the said space and pipe and to open communication between the said space and reserve-fluid chamber.

90 95 10. A tool-piston, its cylinder, pipes for supplying motive fluid alternately to the opposite sides of the piston, a reserve-fluid chamber, a manually-operated valve and passages leading respectively from one of the pipes, from the space at one side of the piston and from the reserve-fluid chamber to the face of the valve, the said valve being arranged to close communication between said space and pipe and to open communication between the said space and reserve-fluid chamber.

100 105 11. A tool-piston, its cylinder, pipes for supplying motive fluid alternately to the opposite sides of the piston, a reserve-fluid chamber, a valve and passages leading respectively from one of the pipes, from the space at the front side of the piston and from the reserve-fluid chamber to the face of the valve, the said valve being arranged to close communication between the space at the front side of the piston and said pipe and to open communication between said space and the reserve-fluid chamber.

110 115 12. A tool-piston, its cylinder, pipes for supplying motive fluid alternately to the opposite sides of the piston, a reserve-fluid chamber, a manually-operated valve and passages leading respectively from one of the pipes, from the space at the front side of the piston and from the reserve-fluid chamber to the face of the valve, said manually-operated valve being arranged to close communication between the space at the front side of the piston and said pipe and to open communication between said space and the reserve-fluid chamber.

120 125 13. A tool-piston, its cylinder, pipes for supplying motive fluid alternately to the opposite sides of the piston, a reserve-fluid chamber.

chamber, means for closing communication between the space at one side of the piston and one of the pipes and opening said space to atmosphere and means for closing communication between the space at the other side of the piston and the other of the pipes and opening communication between said space and the reserve-fluid chamber.

In testimony that I claim the foregoing as my invention I have signed my name, in presence of two witnesses, this 13th day of December, 1905.

Corrections in Letters Patent No. 819,011.

It is hereby certified that in Letters Patent No. 819,011, granted April 24, 1906, upon the application of Arthur H. Gibson, of Easton, Pennsylvania, for an improvement in "Electropneumatic Channelers," errors appear requiring correction, as follows: In the specification and claims, the word "presser" wherever it occurs should read *pressor* and the word "pressers" should read *pressors*; and that the said Letters Patent should be read with these corrections therein that the same may conform to the record of the case in the Patent Office.

Signed and sealed this 15th day of May, A. D., 1906.
